UNITED STATES PATENT OFFICE.

JULIUS H. HOLMGREEN, OF SAN ANTONIO, TEXAS.

MOLD FOR CASTING THE HULLS OF CONCRETE SHIPS.

1,383,118.

Specification of Letters Patent. Patented June 28, 1921.

Application filed October 5, 1918. Serial No. 257,054.

To all whom it may concern:

Be it known that I, JULIUS H. HOLMGREEN, a citizen of the United States, residing at San Antonio, in the county of Bexar and State of Texas, have invented certain new and useful Improvements in Molds for Casting the Hulls of Concrete Ships, of which the following is a specification.

This invention relates to molds for casting the hulls of ships and other floating craft from concrete or similar plastic material.

The object of the invention is to provide an improved mold or form of simple and durable construction from which the cast or molded hull may be conveniently and expeditiously removed without the necessity of withdrawing the form in sections or as a whole in order to release the molded product.

A further object is to provide a mold having a receiving dock associated therewith and adapted to receive the cast hull from the mold, means being provided for floating the hull out of the mold into the dock and subsequently floating said hull from the dock into a launching bay or channel, thereby eliminating liability of fracture or undue strain on both the mold and hull during transition of the latter from the mold to the launching bay or channel and entirely dispensing with the employment of "ways" from which vessels are at present launched into the water.

The invention further aims to provide a stationary or permanent mold which may be used repeatedly without the employment of the usual temporary exterior scaffolding and without the necessity of removing or disassembling the mold to permit launching of the vessel.

A further object is to provide means for insuring the elevation of the hull on an even keel during the discharge of said hull from the mold.

The invention further contemplates the provision of suitable sleeves or thimbles in the walls of the stationary mold, said sleeves being adapted to receive anchoring bolts for holding the inner and outer walls of the mold in proper position during the molding operation and also serving to permit the passage of water therethrough after the hull has been cast and it is desired to float said hull out of the molding chamber.

A further object in view is to provide a

mold including an inner wall having a retaining or buttress wall spaced laterally therefrom to provide an intermediate chamber for the workmen when attaching and releasing the anchoring bolts or otherwise performing work in connection with the molding operation, said inner wall being provided at its upper portion with an offset constituting a walkway for the workmen when introducing concrete within the molding compartment or when adjusting the cross beams for regulating the vertical movement of the hull within the mold.

A still further object of the invention is generally to improve this class of devices so as to increase their utility, durability, and efficiency.

Other and incidental objects will appear during the course of the detailed description of the invention. In the drawings, wherein I have illustrated the preferred embodiment of the invention, and wherein similar reference characters designate corresponding parts throughout the several views:

Figure 1 is a top plan view of a combined mold and receiving dock constructed in accordance with the present invention,

Fig. 2 is a longitudinal sectional view showing the hull within the molding chamber and ready to be released therefrom,

Fig. 3 is a transverse sectional view on the line 3—3 of Fig. 2 and looking in the direction of the arrows,

Fig. 4 is a similar view taken on the line 4—4 of Fig. 2,

Fig. 5 is a similar view taken on the line 5—5 of Fig. 2,

Fig. 6 is a transverse sectional view taken on the line 6—6 of Fig. 1, and showing the cast or molded hull supported on keel blocks within the receiving dock to permit the application of an exterior finish thereto,

Fig. 7 is a transverse sectional view showing the means employed for controlling the vertical movement of the hull within the molding chamber when releasing the hull therefrom,

Fig. 8 is an enlarged detail sectional view of the regulating means shown in Fig. 7,

Fig. 9 is a detail sectional view showing the adjusting means detached and a closure or plug fitting in the upper end of the anchoring rod to close the threaded opening therein,

Fig. 10 is a vertical sectional view show-

ing the manner of holding the inner and outer walls of the mold in position and the manner of supporting the reinforcing rods within the molding compartment during the 5 molding operation,

Fig. 11 is a detail perspective view of a portion of the outer wall of the mold with the anchoring rods removed to permit water to pass through the sleeves when floating the 10 hull out of the molding chamber,

Fig. 12 is a horizontal sectional view showing the manner of molding or casting the ribs of the vessel, and

Fig. 13 is a vertical sectional view taken 15 on the line 13—13 of Fig. 12, showing the manner of reinforcing the ribs.

The combined mold and receiving dock forming the subject matter of the present invention includes an elongated body portion 5 formed of concrete or other suitable material and preferably constructed *in situ* 20 at a point convenient to the launching bay or channel, said body portion being provided with a transverse bridge wall 6 dividing the same into front and rear compartments, one of which constitutes the molding chamber 7 and the other a dock 8 adapted to receive the cast or molded hull from the chamber 7.

30 The body portion comprises an inner wall 9 which constitutes the outer wall of the molding chamber 7 and an outer or buttress wall 10 spaced laterally from the wall 5 to form an intermediate passage or chamber 11 so that workmen may obtain ready access to the exterior of the chamber 7 during the molding operation. The inner and outer walls 10 and 11 of the body are connected by a plurality of vertical reinforcing

40 webs or partitions 12 and one or more horizontal partitions 13, there being suitable openings 14 formed in the vertical webs or partitions 12 to permit workmen to pass from one compartment to the other and also 45 to permit the passage of water entirely around the bottom of the mold when floating the cast or molded hull out of the molding chamber, as will be more fully explained hereinafter. The outer or buttress wall 10

50 is extended vertically above the inner wall 9 to form a retaining wall 15, which preferably extends entirely around the body portion and serves to prevent displacement of the water when the hull is floated out of the molding chamber. The inner wall 9 at its junction with the retaining wall 15 is preferably offset to provide a walkway 16 for the workmen when introducing concrete within the molding chamber or performing 60 other work in connection with the molding operation. The transverse bridge wall 6 is also reinforced by webs or partitions 17 and is provided with a plurality of openings 18 through which water may flow from the 65 chambers formed by the webs 17 in the

bridge wall into the receiving dock when it is desired to fill the latter with water preparatory to receiving the cast or molded hull from the molding chamber. It will here be noted that the bridge wall 6 terminates below the upper edge of the retaining wall 15 so as to permit the hull being floated from the molding chamber into the receiving chamber without interference from said bridge wall. The forward end of the 70 receiving dock is normally closed by suitable gates 19 and on the bottom of said dock are a series of keel blocks 20 upon which the cast hull is adapted to rest, as best shown in Fig. 6 of the drawings, so as to 75 permit the workmen to apply an exterior coating or other finish to the hull. The hull 21 when resting on the keel blocks within the receiving dock will preferably be centered with respect thereto and held in such 80 position by suitable stays 22 which engage shoulders or ledges 23 in the adjacent walls of the dock, as shown.

The outer wall 9 of the molding chamber is formed with a series of transverse openings 24 entirely surrounding the bottom of the mold and also extending up the side walls thereof, said openings 24 being adapted to receive anchoring bolts 25 and when said bolts are removed serving to permit the 90 passage of water through the openings to the molding chamber for the purpose of releasing or elevating the cast hull from said chamber. Fitting within the openings 24 are metallic thimbles 26, the outer edges of 95 which are flared to form flanges 27 which are embedded in the adjacent faces of the wall 9, as best shown in Fig. 11 of the drawings.

The inner wall or shell of the mold 28 is 105 preferably formed of one or more relatively thin metallic plates 28 and is spaced from the outer wall 9 of the mold to form the molding chamber 7, the walls of the molding chamber being supported in spaced parallel 110 relation to each other by means of rod supporting members 29 having their opposite ends provided with threaded sockets 30 one of which is adapted to receive the threaded end of the adjacent anchoring bolt 25 and the other the threaded end of an auxiliary bolt 31. The rod supporting members 29 are formed with circumferential grooves 32 which form seats for suitable reinforcing rods 33 which are preferably disposed within 120 the molding chamber 7 prior to introducing concrete therein. The reinforcing rods 33 extend vertically and horizontally of the molding chamber as well as diagonally thereof and said rods are preferably secured in their circumferential grooves or seats by means of tie wires (not shown) and if desired said rods may be tied together at intervals in order to form a strong reinforcing structure. Arranged within the mold 125 130

ing chamber 7 are spaced strips of wire fabric 34 and bearing against the exterior faces of said strips of fabric are substantially frusto conical washers 35 preferably formed 5 of cement and having conical shaped openings 36 formed therein to permit the passage of the anchoring bolts 25 and 31.

Temporarily secured to the inner face of the wall 9 and covering the openings therein 10 is a sheet of wire netting 37 and covering said wire netting is a relatively thin metallic plate 38 and one or more strips of waterproof paper 39, said elements together constituting a finishing lining for the inner 15 face of the outer wall 9 of the mold. The wire netting 37 preferably extends only a short distance up the sides of the mold but the waterproof paper 39 extends the entire height of the mold. Inasmuch as the wire 20 netting 37 is of the open mesh type, water may readily pass through the sleeves 26, after the anchoring bolts 25 are removed, and thence through the mesh of the wire netting and dislodge the surfacing lining when 25 water is turned into the chambers 11 for the purpose of floating the hull out of the molding chamber. In order to retain the surfacing lining temporarily in position on the wall 9 of the mold, the anchoring bolts 25 30 are omitted from certain of the sleeves 24 and suitable wooden plugs are driven into said sleeves and the wire netting, metal plate and paper strips constituting the lining secured to said wooden plugs by small 35 nails or similar fastening devices capable of being readily withdrawn from the wooden plugs to release the surfacing lining by the action of the water when the latter is admitted for the purpose of floating the hull. 40 It will, of course, be understood that the openings 24 will be relatively close together at the bottom of the mold where it is desired to admit water for the purpose of floating the hull, and that said openings near the 45 upper sides of the mold will be relatively few and far between, the only purpose of these latter openings being to accommodate plugs to support the surfacing lining. In assembling the mold to cast the hull of a 50 ship, the anchoring bolts 25 are first threaded into the sockets 30 and said bolts 25 passed through the open mesh of the outer strip of wire fabric 34, after which the washers 35 are positioned against the wire 55 netting 34 and the bolts 25 passed through said washers and through the surfacing lining and adjacent sleeves 26, nuts 40 being subsequently threaded on the bolts 25 to secure the parts in assembled position, as best 60 shown in Fig. 10 of the drawings. The reinforcing rods 33 are then positioned within the molding chamber 7 and tied in the manner before stated, after which the inner wire screen material 34 is placed against the rod 65 supporting members 29 and the bolts 31

threaded into the adjacent sockets formed in said bolt supporting members. The washers 35 are then fitted over the bolts 31 and the inner plate 28 positioned thereagainst, so that by threading nuts 41 on the bolts 31, the parts may be firmly retained in position. With the parts in the position shown in Fig. 10 of the drawings, the concrete is poured, shoveled, or otherwise introduced into the molding chamber 7 and tamped or otherwise 75 as desired so as to form the walls of the hull of the vessel, as will be readily understood.

In order to form the rudder post of the hull, a filling block 42 is provided, said block being preferably formed of coacting 80 sections connected by tie bolts or rods 43, the heads and nuts of which are countersunk in the adjacent block sections, as indicated at 44 in Fig. 5 of the drawings. The sections comprising the filling block are 85 formed with marginal grooves 45 which, when the sections are assembled, register with each other to form a chamber for the reception of concrete which when molded into shape produces the rudder post 46 of 90 the hull. The upper ends of the block sections 42 are curved to conform to the lower face of the stern of the hull while the side walls of the blocks are inclined or tapered downwardly so as to permit said blocks to 95 be withdrawn with the hull from the molding chamber when floating the hull to released position. It will, of course, be understood that after the hull is removed from the molding chamber, the block sections 42 100 are detached, thus leaving the rudder post spaced from the stern post of the hull to permit the attachment of the usual rudder and propeller. The hull of the vessel is provided at spaced intervals with vertically disposed reinforcing ribs 47 and in order to form these ribs the inner wall 28 of the mold is provided with offset portions 48 conforming to the shape of the ribs 47 and preferably formed in sections detachably united 105 by suitable straps or cleats 49 fitting over studs 50, as best shown in Fig. 12 of the drawings. The ribs 49 are reinforced and strengthened by the provision of a plurality of vertically disposed reinforcing rods 51 110 which are connected by securing stirrups 52 and also by brackets or arms 53, the ends of which are bent laterally at 54 and provided with threaded openings for engagement with the threaded ends of the adjacent anchoring bolts 25. Inclined or diagonal reinforcing bars 55 also preferably form a connection between the rods or brackets 53 and certain of the anchoring bolts 25, as shown. 115

The body portion 5 is provided at spaced intervals with reinforcing lugs 56 preferably cast integral with the inner wall 9 and in which are embedded anchoring rods 57, each provided with a terminal anchor 58, the 120

lower face of which is recessed for the reception of the head 60 of the adjacent anchoring rod, as best shown in Fig. 8 of the drawings. The upper end of each anchoring rod 57 is provided with an enlarged head 61 having a conical socket 62 formed therein, the walls of which are threaded for engagement with the correspondingly threaded end of an adjusting bolt 63. The bolts 63 extend through cross beams 64, the purpose of which is to bear against the hull of the vessel and prevent the same from rising unevenly within the mold when water is introduced beneath the bottom of the hull to release the same or, in other words, to cause the hull to rise on an even keel within the molding chamber. The upper surface of the head 61 of each rod 57 is preferably disposed flush with the walkway 16 and is provided with a countersunk portion 65 adapted to receive a suitable plug or closure 66 which latter is threaded in the socket 62 when the beam 64 and threaded bolt 63 are detached so as to prevent dirt from entering the threaded socket 62 and clogging or otherwise obstructing the same.

In operation, the inner shell or form 28 is placed in juxtaposition with respect to the outer wall of the mold and the reinforcing rods placed within the molding chamber in the manner shown in Fig. 10 of the drawings, after which concrete is poured, shoveled or otherwise introduced into the molding chamber. After the concrete of which the hull is formed has become thoroughly set or solidified, the nuts 40 and anchoring bolts 25 are withdrawn by the workmen in the chamber 11 and water is conveyed by means of a pump 67 from a suitable source 30 of supply into the chambers within the bridge wall 6 and thence into the receiving dock 8, a portion of the water passing through the sleeves 26 and through the mesh of the wire netting, displacing the 45 surface lining at the bottom of the hull and causing the hull to float in a vertical plane out of the molding chamber and into the receiving dock. Should one end of the hull be lighter than the other and tend to float 50 or rise more quickly, said hull may be maintained on an even keel during its vertical travel to the top of the mold by adjusting the cross beams 64, as will be readily understood. After the hull has been floated in a 55 vertical plane to a position above the receiving dock, the water in the dock is exhausted or discharged therefrom, thus allowing the hull to settle within the dock and rest on the keel blocks 20. The inner shell 60 or form 26 may be removed either before releasing the hull from the molding chamber or after the hull has been transferred to the receiving dock for application of an exterior finish thereto. After the inner shell 65 has been removed and prior to the applica-

tion of an exterior finish to the hull, the openings in the spacing washers or disks 35 are filled with concrete and owing to the peculiar shape of said disks it will be seen that the latter will be effectually anchored 70 within the walls of the hull. After the exterior finish has been applied to the hull of the vessel, the latter may be readily floated into the launching bay or channel by opening the gates 19, as will be readily understood. By exhausting the surplus water in both the receiving dock and molding chamber, the latter may be again used for molding a hull, thus permitting the device to be used over and over again without the 75 employment of temporary exterior scaffolding and without the necessity of withdrawing the form in sections or as a whole in order to release the molded product. The construction and arrangement of the mold 80 also eliminates liability of fracture or undue strain on both mold and hull during transition of the latter from the mold to the launching bay or channel and entirely dispenses with the employment of "ways" 85 from which vessels are usually launched into the water.

While I have described in detail the method employed in constructing and floating the hulls of concrete ships, it may be 90 here stated that said method forms the subject matter of a separate application, executed of even date herewith, and that no claim is made in this application thereto, the present invention being confined to the 95 mechanical construction of the mold or apparatus *per se*.

Having thus described the invention, what is claimed as new is:

1. A mold for casting the hulls of ships 100 from concrete comprising a chamber constituting a mold, a docking chamber adjacent thereto, and a dividing wall common to both chambers, said chambers being in communication with each other over said dividing 110 wall.

2. A mold for casting the hulls of ships from concrete comprising a chamber conforming to the shape of the hull to be cast and constituting a mold, a docking chamber disposed in juxtaposition to the first mentioned chamber, and a dividing wall common to both chambers, said chambers being in communication with each other over said dividing wall. 115

3. A mold for casting the hulls of ships from concrete including a body portion having a bridge wall dividing the body portion into spaced chambers one of which constitutes a mold and the other a dock adapted to receive the cast hull from said mold. 125

4. A mold for casting the hulls of ships from concrete including a body portion having a bridge wall of less height than the body portion and dividing said body por- 130

tion into spaced chambers one of which constitutes a mold and the other a dock adapted to receive the cast hull from said mold, and a gate forming a closure for one end of the receiving dock.

5. A mold for casting the hulls of ships from concrete including an outer form having a buttressing wall spaced therefrom to form an intermediate chamber, an inner

10 form spaced from the outer form to form a molding compartment, the buttressing wall being extended above the outer form of the mold to form a retaining wall, there being openings formed in the wall of the outer 15 form and communicating with the intermediate chamber whereby water introduced into the intermediate chamber will pass through said openings and float the cast hull out of the molding compartment.

20 6. A mold for casting the hulls of ships from concrete including an outer form having a buttressing wall spaced therefrom to form an intermediate chamber, the buttressing wall being extended above the outer 25 form to form a retaining wall and said outer form being offset at its junction with the retaining wall to form a walkway, an inner form spaced from the outer form to produce an intermediate molding compartment, there 30 being openings formed in the outer wall and communicating with the intermediate chamber to permit the passage of water through said openings into the molding chamber to float the hull therefrom.

35 7. A mold for casting the hulls of ships from concrete including an elongated body portion the outer wall of which constitutes a buttressing wall, an outer form spaced from the buttressing wall to form a circumferential passage, spaced partitions disposed 40 within the passage and communicating with each other to form a plurality of chambers, a bridge wall disposed within the body portion and forming one end of a receiving 45 dock, said bridge wall being provided with chambers having openings therein communicating with the receiving dock, an inner form spaced from the outer form to form a molding compartment, and a gate forming 50 a closure for one end of the receiving dock, there being openings formed in the outer wall of the molding compartment to permit the passage of water therethrough for the purpose of releasing the cast hull from the 55 mold.

8. A mold for casting the hulls of ships from concrete including an elongated body portion, the outer wall of which constitutes a buttressing wall, an inner form spaced 60 from the buttressing wall to form an intermediate chamber, the outer form being offset to form a walkway and the buttressing wall being extended upwardly above the walkway to produce a retaining wall, a 65 bridge wall of less height than the retain-

ing wall and forming one end of a receiving dock, an inner form spaced from the outer form to produce a molding chamber, there being openings formed in the outer wall of the mold and openings formed in the bridge 70 wall and communicating with the receiving dock, and means for introducing water simultaneously into the receiving dock and through said openings to release the hull from the mold.

75 9. A mold for casting the hulls of ships from concrete including a body portion the outer wall of which constitutes a buttressing wall, an outer form spaced from the buttressing wall to form an intermediate 80 chamber, the outer form being of less height than the buttressing wall and offset with respect thereto to form a walkway, an inner form spaced from the outer form to form a molding chamber, anchoring rods 85 embedded in the body portion and having their upper ends provided with heads formed with threaded sockets, vertically adjustable cross beams extending transversely across the molding chamber and adapted to 90 rest upon the molded product therein, and adjusting screws extending through the beams and engaging the threaded sockets in the anchoring rods for adjusting said cross beams, there being openings formed in 95 the outer form of the mold to permit the passage of water therethrough for floating the cast hull out of the mold.

10. A mold for casting the hulls of vessels from concrete comprising inner and outer 100 forms spaced apart to form a molding chamber, sectional blocks having registering grooves formed in the mating faces thereof for forming the rudder post of the hull, the sides of said blocks being inclined 105 downwardly and said blocks being removable with the hull from the molding chamber, and means for introducing water within the molding chamber and beneath the cast hull for releasing the hull and sectional blocks from the mold.

11. A mold for casting the hulls of ships from concrete comprising inner and outer walls spaced apart to produce a molding chamber, one of said walls being provided 115 with spaced openings having sleeves seated therein, means disposed within the molding chamber for supporting reinforcing rods, and anchoring bolts extending through the sleeves and engaging the rod supporting 120 means, the bolts within certain of the sleeves being adapted to be removed to permit the passage of water therethrough for floating the cast hull out of the mold.

12. A mold for casting the hulls of ships 125 from concrete comprising inner and outer walls spaced apart to form a molding chamber, the outer wall being provided with openings having sleeves seated therein, a finishing lining for the inner face of the outer 130

wall and normally covering the openings therein, rod supporting members arranged within the molding chamber, and anchoring bolts extending through the sleeves and engaging the rod supporting members, the bolts within certain of the sleeves being adapted to be removed to permit the passage of water therethrough for dislodging the finishing lining and floating the cast hull out of the mold.

13. A mold for casting the hulls of ships from concrete comprising inner and outer walls spaced apart to form an intermediate molding chamber, the outer wall being thicker than the inner wall and provided with openings having sleeves fitted therein, rod supporting members disposed within the molding chamber, anchoring bolts extending through the sleeves and detachably engaging the rod supporting members, auxiliary anchoring bolts extending through the inner wall of the molding chamber and engaging said rod supporting members, and nuts engaging the anchoring bolts for holding the parts in assembled position during the molding operation, certain of the an-

choring bolts being adapted to be removed from the sleeves to permit the passage of water therethrough for the purpose of floating the cast hull out of the mold.

30

14. A mold for casting the hulls of ships from concrete comprising inner and outer walls spaced apart to form a molding chamber, the outer wall being provided with openings, a readily separable finishing lining secured to the inner face of the outer wall and normally covering the openings therein and comprising an outer layer of foraminous material, an inner layer of waterproof material and an intermediate imperforate plate, rod supporting members arranged within the molding chamber, and anchoring bolts extending through the openings and engaging the rod supporting members, the bolts within certain of the openings being adapted to be removed to permit the passage of water therethrough for dislodging the finishing lining and floating the cast hull out of the mold.

35

15. In testimony whereof I affix my signature. 40

45 JULIUS H. HOLMGREEN. [L. S.] 50
